Primary Examiner — Katrina N Gonzalez

(57) **CLAIM**

The ornamental design for a remote control for dog training collar device, as shown and described.

DESCRIPTION

FIG. 1 is a perspective view of a remote control for dog training collar device showing my new design;
FIG. 2 is another perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;
FIG. 9 is an enlarged view of portion 9 shown in FIG. 1;
FIG. 10 is an enlarged view of portion 10 shown in FIG. 1;
FIG. 11 is an enlarged view of portion 11 shown in FIG. 2;
FIG. 12 is an enlarged view of portion 12 shown in FIG. 5;
FIG. 13 is an enlarged view of portion 13 shown in FIG. 6;
and,
FIG. 14 is an enlarged view of portion 14 shown in FIG. 8. The dash-dash broken lines in the drawings depict portions of the remote control for dog training collar device. The dot-dash broken lines represent the boundaries of the enlarged views. The broken lines form no part of the claimed design.

1 Claim, 14 Drawing Sheets
